UNITED STATES PATENT OFFICE.

FREDERICK W. MCKOWN, OF NEW YORK, N. Y., ASSIGNOR TO WESTERN ELECTRIC COMPANY, INCORPORATED, OF NEW YORK, N. Y., A CORPORATION OF NEW YORK.

ANTI-SIDE-TONE SUBSTATION CIRCUIT.

Application filed July 17, 1919. Serial No. 311,543.

To all whom it may concern:

Be it known that I, FREDERICK W. MCKOWN, a citizen of the United States, residing at New York, in the county of New York, State of New York, have invented certain new and useful Improvements in Anti-Side-Tone Substation Circuits, of which the following is a full, clear, concise, and exact description.

10 This invention relates to anti-side-tone telephone substation circuits.

An object of the invention is to provide a telephone substation which will be anti-side-tone without the employment of a transformer and which will permit the energization of the transmitter by current from a common battery.

For this purpose a two-winding receiver is employed and the transmitter, line wires and in the preferred form an auxiliary impedance are so connected to these windings that, on transmitting, the alternating current is divided between the two windings in such a way that the ampere turns in the 25 windings are substantially equal and opposite so that the current produces substantially no effect on the receiver diaphragm. On receiving, currents from the line may pass through the windings in such a manner that their effects on the receiver will be at a maximum. Preferably the relations are such that on receiving substantially no current flows in the auxiliary impedance nor in the winding associated therewith.

30 A further object of the invention is to design a circuit of the above type which will be specially adapted for use in a hand set substation. Under some conditions it may be desirable to locate in the ringer box the condenser or condensers necessary for controlling the flow of direct current and for balancing the capacity of the line. In the form of the invention which it is preferred to use where possible a single condenser in 35 the ringer box serves the three fold function of preventing direct current from being shunted around the transmitter, providing a path for ringing currents and balancing the capacity of the line.

40 These and other objects of the invention will be more fully understood from the following detailed description and claims taken in connection with the accompanying drawings in which

Fig. 1 is a diagrammatic representation 55 of one form of my invention;

Fig. 2 is a modification in which a single condenser takes the place of the two condensers shown in Fig. 1;

Fig. 3 is a modification in which two condensers are placed in the ringer box;

Fig. 4 is a circuit diagram illustrating the flow of currents in transmitting;

Fig. 5 is a similar view illustrating the 65 flow of currents in receiving;

Fig. 6 is a circuit diagram showing the invention applied to a bi-polar receiver; and

Fig. 7 is a schematic showing of the circuit employed in Fig. 2.

Referring to the drawings by reference numerals, the hand set 10 comprises the transmitter 11 and the receiver 12. On the receiver core 13 are two windings 14 and 15, their adjacent ends being connected by conductor 16 to the transmitter 11. The winding 14 may be partially or wholly formed of resistance wire for a purpose which will be explained later on.

The leads 17 and 18 from windings 14 and 15 are connected to the apparatus in the 80 ringer box 19 by the cord conductors 20 and 21 respectively, conductor 20 being connected directly to line wire 22. Conductor 21 is adapted to be connected to the other line wire 23 when the hand set is removed 85 from the hook 24.

The transmitter 11 is connected by lead 25 to lead 17 at 26, and it will be seen that the transmitter is energized by direct current from the central battery indicated at 90 27. A condenser 28 is provided to prevent the flow of direct current in the branch of the circuit including winding 14 and also to balance the capacity of the line as will be later explained. The ringer 29 and condenser 30 are bridged directly across the line.

The operation of the circuit of Fig. 1 will be more easily understood from the simplified diagrams of Fig. 4 and Fig. 5. 100 The impedance of the line as seen from the substation generally consists of a resistance component and a small capacity component. The resistance 31 is designed to balance the resistance of the line and the condenser 28 to balance the capacity of the line. Fig. 4 shows the direction of current flow on transmitting. The current divides between wind-

ings 14 and 15. The ratio of these windings to each other and the relation of the impedance of the auxiliary resistance 31 and condenser 28 to the impedance of the line are so designed that the ampere turns in the two windings are equal, thus producing substantially no effect on the receiver diaphragm. For the purpose of saving space the auxiliary resistance 31 is preferably incorporated in the winding 14, as above stated.

The current flow on receiving, as shown in Fig. 5, is through the transmitter 11 and winding 15, substantially no current flowing through auxiliary resistance 31 and winding 14 on account of the voltage induced in winding 14 by the current in winding 15. Considerable variation from this condition, however, can be had without greatly interfering with the efficiency of the set. Reference is made to U. S. Patent to George A. Campbell, 1,254,472, January 22, 1918, for a discussion of the general principles involved in designing substation circuits employing an auxiliary resistance which is conjugate to the impedance of the line. As pointed out in this patent the impedance of the transmitter should be such with respect to the impedance of the line and the other elements of the substation circuit, that the transmitter in operating, works into an impedance approximately equal to its own impedance.

In case it is not feasible to place the condenser 28 in the hand set, the arrangements shown in Fig. 2 or Fig. 3 may be employed. In Fig. 2 the single condenser 28' is so positioned that it is in series with the ringer when the hook 24 is down, and also in a series circuit with winding 14 when the hook is up. In this arrangement terminal 26' corresponds to terminal 26 in Fig. 1, conductor 25' being extended to the ringer box and an additional switch 32 being provided to break the circuit through the transmitter when the substation is idle. This arrangement is shown schematically in Fig. 7.

The arrangement of Fig. 3 is like that of Fig. 1 except that the condenser 28 is placed in the ringer box and the conductor 25' is extended from the transmitter to the ringer box.

The operation of the circuits of Figs. 2 and 3 is substantially identical with that of Fig. 1.

In Fig. 6 the invention is shown applied to a substation having a receiver with a bipolar magnet 23. Since in this form there is negligible mutual impedance between the receiver windings, the balancing resistance 31 may be omitted and absence of side-tone may be secured by properly proportioning the number of turns in each winding.

While the circuits disclosed herein are

adapted for use in any telephone substation wherein the transmitter is energized by current from a central station, they are particularly well adapted for use in substations employing handsets, in which there is inherently a greater tendency to singeing because of the mechanical connection between the receiver and the transmitter.

What is claimed is:

1. In combination with a common battery telephone line, a side tone reduction substation circuit comprising two branches, a telephone transmitter in a conductor common to said branches and adapted to be energized by direct current from the common battery, a telephone receiver having a magnetic core, a plurality of differentially wound windings on said core each of said branches having directly included therein one of said windings, one of said branches being adapted to be connected to the line, and the other of said branches forming a closed loop, the individual portion of said other branch having sufficient impedance to balance the line included in said first branch, said transmitter having such an impedance with respect to the line and the other elements of the substation circuit, that the transmitter when operated works into an impedance of the order of the impedance of the transmitter.

2. In combination with a common battery telephone line, an anti-side-tone substation circuit comprising two branches, a telephone transmitter in a conductor common to said branches and adapted to be energized by direct current from the common battery, a telephone receiver having a magnetic core, a plurality of differentially wound windings on said core, each of said branches having directly included therein one of said windings, one of said branches being adapted to be connected to the line, and the other of said branches forming a closed loop, the individual portion of said other branch having sufficient resistance to balance the resistance of the line, and sufficient capacity to balance the capacity of the line, the elements of said circuit having such impedance, and being so arranged that currents from the transmitter do not appreciably actuate the receiver, and currents received from the line do not appreciably flow through the individual portion of said other branch, said transmitter having such an impedance with respect to the line and the other elements of the substation circuit, that the transmitter when operated works into an impedance of the order of the impedance of the transmitter.

3. An anti-side-tone substation circuit comprising two branches, a receiver having a plurality of differentially wound windings, one of said windings being included in each of said branches, one of said branches being adapted to be connected to a line, and the other of said branches forming a closed

loop, said closed loop comprising a series condenser, and a ringer adapted to be connected across said line, said condenser being so located as to prevent the flow of direct current through said ringer.

4. An anti-side-tone substation circuit comprising two branches, a receiver having a plurality of differentially wound windings, one of said windings being included in each of said branches, one of said branches being adapted to be connected to a line, the other of said branches forming a closed loop, said closed loop comprising a series condenser, a ringer adapted to be connected across said line, said condenser being so located as to prevent the flow of direct current through said ringer, and a transmitter in a conductor common to said branches and adapted to be energized by direct current from said line.

5. In combination with a telephone line, a substation set comprising a transmitter and receiver, switching means for connect-

ing to or disconnecting from the line said transmitter and said receiver, a shunt path around said transmitter when the transmitter is connected to the line, a ringer, a condenser in series with said ringer and the line, and contacts and connections operated when said transmitter and said receiver are connected to the line for connecting said condenser in said shunt path for preventing direct current from being shunted around said transmitter.

6. A telephone circuit having two branches one of said branches comprising a line and the other of said branches comprising a resistance designed to balance the resistance of said line and a condenser designed to balance the capacity of said line, a receiver winding in each of said branches, and means for producing a flow of direct current in said first circuit branch.

In witness whereof, I hereunto subscribe my name this 14th day of July, A. D. 1919.

FREDERICK W. McKOWN.
